UNITED STATES PATENT OFFICE

JOSEPH SCHECHTER, OF BROOKLYN, AND CHARLES R. POOLE, OF NEW YORK, N. Y.,
ASSIGNORS TO SEGAL LOCK & HARDWARE CO. INC., OF NEW YORK, N. Y., A CORPORATION OF NEW YORK.

LOCK

Application filed April 12, 1930. Serial No. 443,662.

This invention relates to a lock having structurally and functionally improved characteristics.

It is an object of the invention to provide a device of this character, the parts of which will be relatively few in number and individually simple and rugged in construction, these parts being capable of manufacture to the largest extent by a minimum of manual labor, and when so manufactured, being capable of ready assemblage to provide a lock operating over long periods of time with freedom from mechanical difficulties.

A further object of the invention is that of providing a lock which will be virtually jimmie-proof, i.e. incapable of being forced open by means of a lever or other similar implement.

With these and further objects in mind, reference is had to the attached sheet of drawings illustrating one practical embodiment of the invention, and in which:

Fig. 1 is a rear view of a lock casing with cover plate broken away to disclose the underlying construction, the bolt in this position being wholly projected.

Fig. 2 is a transverse sectional view taken along the lines 2--2 and in the direction of the arrows of Fig. 1.

Fig. 3 is a view similar to Fig. 1, but showing the bolt in its initial stages of retraction; and

Fig. 4 is a view similar to Fig. 3 but showing a bolt retracted to a greater extent and illustrating the end of the latter in section.

In these views, the numeral 5 indicates the lock casing formed with an open face to which there is applied a cover plate 6 to enclose the mechanism of the lock. In accordance with conventional construction, one edge of the casing is formed with an opening through which the bolt may be projected and retracted. In the embodiment under consideration, this bolt includes a body 7 formed with a slot or notch 8 across which a subsidiary or supplemental bolt 9 may be projected, it being observed as in Figs. 3 and 4, that the bolt 7 is formed with bores, one receiving the supplemental bolt when the latter is retracted and the other—indicated at 10—

receiving the outer end of this bolt when the latter is projected. It will be understood that a keeper of suitable construction is provided to receive the bolt 7 and that this keeper is formed with a loop portion or the equivalent thereof which when the bolt 7 is projected extends into the notch 8 and through the bore of which the supplemental bolt 9 projects in order to interlock the parts.

This keeper has not been illustrated in the annexed drawings in that many forms thereof have been previously employed. Moreover, it will be noted that according to the form of the casing herein illustrated, the lock is of the "sill type". It is obvious, aside from the fact that all parts of the lock might be constructed of any desirable material that the construction of the casing and associated parts might be modified in any respect necessary to create a "mortise" type lock.

With a view to operating the lock, i.e. projecting and retracting the bolts, it is preferred, according to the present invention to associate with one face of the casing a handle or knob 11 which is rotatably carried by this casing and terminates in a crank portion 12 having a stud which enters a recess formed in the rear face of an extension 13 of the bolt operating member 14. This extension may carry upon its outer face an interrupted collar portion 15 for cooperation with a projection 16 forming a part of a crank member 17 associated with the cover plate. This crank member in accordance with usual practice may receive the tail piece of a key mechanism which upon rotation will serve to turn the crank and cause the projection to bear against the inner face of the collar 15. Thus, either the crank 12 or the crank 17 will cause force to be exerted upon the extension 13 of the member 14.

The bolt 7 has a rear portion 18 terminating in an extension 19. This extension rides between a block 20 and a lug 21, both preferably forming integral parts of the casing, and thus this extension will be guided in its movements. A block 22 may also form an integral part of the casing and bear against the side face of the extension in addition to serving in cooperation with a pin 23 carried by the

- latter as a stop to limit the projection of the bolt. The bolt also carries a pin 24 which extends through a slot 25 formed in the body 14 of the bolt actuating member, and thus the latter element is also guided and restrained from improper movements, it being borne in mind that the forward edge of this member rides against the rear edge of the bolt 7.
- 5 Thus, it will be understood that as the cranks 12 or 17 are rotated, a thrust will be exerted through the extension 13 and body 14 to the bolt 7. Primarily—considering that the parts are in a position illustrated in Fig. 1—rotation of the crank will cause an elevating of the member 14 and then a retraction of the latter, and finally, a subsequent downward movement of the same. This will obviously cause a retraction of the bolt 7 to a position substantially in line with the forward face of the casing 5.

With a view to shifting the supplemental bolt, it will be observed that a lever 26 is employed, the forward end of which terminates preferably in a circular bearing face or head 27 lying within a recess formed in the upper end of the supplemental bolt. This lever is pivotally carried by the body 14 by virtue of having a pin 28 secured to it which extends 25 through an opening in this body. The rear end of the lever is notched as at 29 and cooperates with a pin 30 secured to the rear portion 18 of the bolt, it being finally noted that the lever is interposed between the body 14 and this rear bolt portion. Thus, with the parts as shown in Fig. 1, it will be obvious that initial movement on the part of the crank 12 will cause, as has been illustrated in Fig. 3, an upward movement on the part of the body 14. This will carry with it the lever 26 and due to the fact that the pin 30 is riding within the notch 29, this action will cause the outer end of the lever to be rocked upwardly, thus wholly retracting the supplemental bolt 9. Thereafter, this bolt will be carried in retracted position during the retraction of the bolt 7 as has been shown in Fig. 4 and subsequently as the body 14 moves downwardly, the parts will again reach the 30 position shown in Fig. 1—insofar as the projection of the supplemental bolt is concerned. A projection of the parts will obviously be effected under a reversal of the foregoing procedure, and thus it will be obvious that the supplemental bolt will at no time be projected until the main bolt is wholly projected and accordingly the opening of the keeper is in line with the path of travel of the supplemental bolt. Also, and conversely, 35 a complete retraction of the supplemental bolt will occur before the main bolt begins to retract.

With a view to preventing any probability of an unauthorized retraction of the bolt, it 35 will be noted that the body 14 is extended

to a point at which it projects materially beyond the extension 19 of the main bolt when the latter is wholly projected. An additional lug 31 forms preferably an integral part of the casing and is spaced from the forward edge of the latter to an extent such as to accommodate the body 14. Accordingly, within the casing, an additional locking expedient is provided, and it will be obvious that if pressure is brought to bear against the bolt 7 in an attempt to force the same rearwardly, that aside from any cooperation of the supplemental bolt 9 with the keeper such movement will be prevented due to the engagement between the rear edge of the body 14 and the lug 31. This, of course, is supplemental to the additional action preventative factor occurring due to the fact that the crank 12 and/or 17 will be in a position where it will be necessary to effect a turning thereof in order to permit of rearward movement of the extension 13 and accordingly the body 14 and associated structure. Finally, it will be observed with a view to assisting the bolt action and also to present an accidental movement of the parts that a spring 32 may be provided which has one of its ends bearing conveniently against the base of a slot formed in the rear edge of the bolt 7, its body being coiled around the pin 24 and its opposite end bearing against the pin 28 carried by the lever 26.

From the foregoing, it will be appreciated that among others, the several objects as specifically aforementioned are achieved. Additionally, it will be understood that a lock is provided which includes a minimum number of parts and is capable of manufacture at a comparatively nominal figure.

In conclusion, it is to be understood that numerous changes in construction and rearrangements of the parts might be resorted to without departing from the spirit of the invention as defined by the claims.

Having described our invention, what we claim as new and desire to secure by Letters Patent, is:

1. A lock including, in combination, a casing, a bolt projectible and retractible with respect to said casing, a supplemental bolt associated with said first named bolt, a lever rockingly supported by said first named bolt and connected to said supplemental bolt to shift the latter, a plate shiftably carried by said first named bolt and connected to said lever, means for shifting said plate, and means associated with said casing and engaging said plate to prevent a forcible retraction of said first named bolt.

2. A lock including, in combination, a casing, a bolt projectible and retractible with respect to said casing, a supplemental bolt carried by said first named bolt, a lever slideable with respect to said bolt and connected to said supplemental bolt to shift the latter,

a plate slidably mounted on said first named bolt and pivotally carrying said lever, and means for moving said plate to effect movements of said first named and supplemental bolts.

5. 3. A lock including, in combination, a casing, a bolt projectible and retractible with respect to said casing, a supplemental bolt carried by said first named bolt, a lever slid-
10 able with respect to said bolt and connected to said supplemental bolt to shift the latter, a plate slidably mounted on said first named bolt and pivotally carrying said lever, means for moving said plate to effect movements of said first named and supplemental bolts,
15 and guide means between said first named bolt and said plate to define the path of travel of the latter over the former.

4. A lock including, in combination, a cas-
20 ing, a bolt projectible and retractible with respect to said casing, a supplemental bolt carried by said first named bolt, a lever slid-
able with respect to said bolt and connected to said supplemental bolt to shift the latter, a
25 plate slidably mounted on said first named bolt and pivotally carrying said lever, means for moving said plate to effect movements of said first named and supplemental bolts,
30 guide means between said first named bolt and said plate to define the path of travel of the latter over the former, and yielding
35 means cooperating with said plate to normally maintain the same in a predetermined position with respect to said first named bolt.

5. A lock including, in combination, a cas-
35 ing, a bolt projectible and retractible with respect to said casing, a supplemental bolt associated with said first named bolt, a plate shiftably carried by said first named bolt, a
40 lever rockingly supported by said plate and connected to said supplemental bolt to actuate the latter and means for shifting said plate.

6. A lock including, in combination, a cas-
45 ing, a bolt projectible and retractible with respect to said casing, a supplemental bolt associated with said first named bolt, a plate shiftably carried by said first named bolt, a lever rockingly supported by said plate and connected to said supplemental bolt to actuate
50 the latter, an extension forming a part of said plate and means engaging said ex-
tension for shifting said lever and plate.

7. A lock including, in combination, a cas-
55 ing, a bolt projectible and retractible with respect to said casing, a supplemental bolt carried by said first named bolt, a plate as-
sociated with said first named bolt, a lever mounted on said plate and adapted to actuate said supplemental bolt said lever being dis-
60 posed to lie against one of the faces of said first named bolt and means for shifting said plate to effect movement of both of said bolts.

8. A lock including, in combination, a cas-
65 ing, a bolt projectible and retractible with respect to said casing, a supplemental bolt

carried by said first named bolt, a plate as-
sociated with said first named bolt, a lever mounted on said plate and adapted to actuate said supplemental bolt, said lever being dis-
65 posed to lie against one of the faces of said first named bolt, means for shifting said plate to effect a movement of both of said bolts
70 and a plurality of stop elements carried by said first named bolt to arrest the projection of the same and effect a further projection
75 of said supplemental bolt.

In testimony whereof we affix our signa-
tures.

JOSEPH SCHECHTER.
CHARLES R. POOLE.
